DEFECT CARD RECEPTACLE

Frederick W. Hankins, Philadelphia, Pa., assignor to The Pennsylvania Railroad Company, Philadelphia, Pa., a corporation of Pennsylvania

Application July 25, 1938, Serial No. 221,162

3 Claims. (Cl. 40—19)

This invention relates to receptacles for use on railway cars for holding papers or objects which need protection from the weather, as well as from blowing away. It is especially adapted for use on railway freight cars to hold so-called defect cards, and is hereinafter explained with special reference to this use.

When a freight car in service develops a defect, it is the duty of the trainman observing it to make out a written record indicating the nature of the defect, which is placed in a receptacle provided on the car for the purpose. The "Rules of Interchange", governing freight equipment on the various railroads, require that every freight car be equipped with such a receptacle. It is very important that the defect card should be securely held and preserved in the receptacle, as a notice of the defect to others afterward handling the car, as well as for the information of the repair shop, to which the car should be sent as soon as practicable. I aim to provide a receptacle which, besides meeting these requirements, will be easy and economical to manufacture and install, rugged and thoroughly water-proof in service, and easy and convenient to use. Other features of the invention will appear from the following description of a species or form of embodiment, and from the drawing. All the features and combinations shown or described are of my invention, so far as novel over the prior art.

In the drawing, Fig. I is a side view of a defect card receptacle installed on a car side, the receptacle being shown with a corner broken out and in section; Fig. II is a plan view of this receptacle, with one end shown in section; and Fig. III is an end view from the left of Fig. I.

Fig. IV is an end view of the receptacle from the right of Fig. I, with the cover plate open, showing the receptacle attached to an upright car wall as in service.

As here shown, the receptacle comprises a suitable length of metal tube 10 with one end closed at 11, with a lateral mounting plate or bracket 12 on one side of the tube, and with a swinging cover 13 at the other end of the tube. Galvanized wrought iron or steel pipe of $1\frac{1}{4}$ inch size is very suitable for the tube 10, and its end may be closed at 11 by welding in a sheet metal disc about $\frac{1}{8}$ inch thick, as indicated at 14. The mounting or bracket plate 12 may be laterally welded to the tube 10 as indicated at 15, and may be welded to the car wall 16 on which the receptacle is used along its upper and lower edges, as indicated at 17 in Figs. I and IV. In prac-

tice, it is desirable to mount the device on the car side adjacent the usual destination-card holder or "board" (not shown). As shown in Figs. III and IV, the bracket plate 12 is intermediately bent to provide a reentrant seat in its mid-portion, for accommodating the curved side of the tube 10; and this seat is preferably curved in an arc conformable to the curvature of the tube. At or about the ends of the curved seat, the plate 12 is reversely bent to bring its ends back into (or beyond) the plane of its middle, so that it will lie flat against the car wall 16. Accordingly, the welds 15, 15 at and beyond the reverse bends of the plate 12 lie well apart (a distance approximating the internal diameter of the tube 10), giving great strength of attachment of the tube to the bracket plate. Also, the edge surfaces at the ends of the plate 12 lie at an angle to one another, and hence make acute angles with the car wall 16 to which they are welded— 20 tending toward the easy formation of very strong welds 17 for attaching the plate 12 to the car wall. The tube 10 may have drainage holes 18, 19 in its lower side to drain out moisture of condensation from its inner surface, one of these 25 being shown at its inner (closed) end and the other near its outer (mouth) end. The cover 13 may consist of a flat plate of sheet metal pivoted by a rivet 20 to a flange or ear 21 extending upward from the tube 10 at its open end. This 30 ear or lug 21 may consist of a block of metal welded to the outside of the tube along its corners 22, 22. As shown in Fig. IV, the cover plate 13 is a diamond-like hexagonal in outline.

As shown in Fig. IV, the cover pivot 20 extends 35 lengthwise of the tube 10, parallel with its axis, so that the cover 13 swings open and shut across the end of the tube, rather than toward and from it. Preferably, the pivot 20 is located above the bore of the tube 10 and to the same side of the tube axis as the bracket 12, so that gravity tends to swing the cover 13 shut, as shown in Fig. III and in dot-and-dash lines in Fig. IV. At the opposite side of the tube from the bracket 12, the cover 13 may have a lateral projection 45 23, formed by bending the sheet metal of the cover at one corner, for engaging against the side or edge of the tube to prevent the cover from swinging beyond its proper closed position. The cover 13 may also have a hand portion 25 projecting downward beyond the tube wall, to afford a convenient finger piece. As will be apparent from the full line open position of the cover 13 in Fig. IV, the relations of pivot 20 and bracket 12 in this figure are such that the up- 50 55

ward-opening swing of the cover will be limited by engagement of its corner 23 and edge 26 against the upright car wall 16. If the wall 16 lies close enough to the tube, it may also be relied on to prevent the cover 13 from swinging beyond proper closed position; and in this case the projection 23 may be dispensed with.

In use, the receptacle is attached to the side or end of a car by the mounting plate or bracket 12, which may be welded to the car along its upper and lower edges as in Figs. I and IV. Accordingly, the thickness of the bracket plate 12 intervenes between the car wall 16 and the casing 10 to space the casing from the wall. Being narrow as compared with the length of the casing 10, as shown, the plate 12 provides passage between the casing and the car wall for the drainage of moisture running down the car wall in wet weather. Normally, the cover 13 is held shut by gravity, as in Figs. III and IV. With the pivot 20 well over toward the bracket 12 and the wall 16, as in Fig. IV, and with a metal cover plate 13 about $\frac{1}{8}$ inch thick, and correspondingly heavy, the cover 13 will not jar open. Even if it should jar completely open, its engagement against the car wall 16 will preclude its approaching dead center over the pivot 20, so that it cannot remain open. Yet it is easily opened fully by its handle portion 25 when a defect card (not shown) is to be inserted or removed. The card may, of course, be bent or rolled for insertion in the tube 10, so as to be held securely in place by its resilient tendency to straighten out or unroll.

Having thus described my invention, I claim:

1. A card receptacle, to be affixed to a railway car wall in horizontal position, comprising a tubular metal casing permanently closed at one end, a bracket plate attached to said casing at one side of the casing having car-wall-engaging portions in a plane substantially parallel with the axis of the casing, and a movable cover for the other end of the casing pivoted to the casing at the top thereof, about an axis off-center with respect to the axis of the casing; said cover having a portion which when the bracket plate is affixed to a car wall and the cover is turned upward above the casing, to a position short of dead-center with respect to the pivot but leaving the casing end open, extends to one side of the casing to the plane of said wall-engaging portions of said bracket plate, so as to engage the car wall and stop the cover in such position.

2. A card receptacle as set forth in claim 1 wherein the bracket plate is narrow as compared with the length of the casing and extends across the side of the casing to which it is attached, so that when said bracket plate is affixed to a car wall, its thickness intervenes between the wall and the side of the casing.

3. A card receptacle as set forth in claim 1 wherein the bracket plate is laterally recessed to receive a rounded side of the tubular casing and is attached to said casing side along the edges of its lateral recess.

FREDERICK W. HANKINS.
